VENTILATING DEVICE

Karl M. Ganger and John B. Burrowes, Dayton,
Ohio, assignors to The Lau Blower Company,
Dayton, Ohio, a corporation of Ohio

Application March 10, 1947, Serial No. 733,494

10 Claims. (Cl. 230—259)

1

This invention relates to ventilating fans.

One of the principal objects of the invention is to provide a portable ventilating fan of simple and lightweight but strong construction which is adapted to be placed before a window for exhaust purposes or to draw in fresh air and which is self supporting and requires no special mounting.

An additional object is to provide such a ventilating fan which will be highly compact, particularly from front to back, and which is constructed to offer maximum protection both to the fan blades and motor and also to any person or object coming in contact therewith.

Another object is to provide such a portable ventilating fan wherein the operating parts are constructed and arranged for ready concealment by grill work or the like which both shields these parts from view to enhance the appearance of the fan and also protects both the fan and the user.

It is also an object of the invention to provide a portable ventilating fan wherein all parts are mounted on a single main panel provided with legs adapted to support the fan in a desired operating position without other installation.

A further object is to provide a portable ventilating fan wherein the screen or grill surrounding at least a portion of the fan blades and motor also serves to brace the framework of the fan and thus to aid in supporting the weight of the motor and absorbing the vibrations incident to use.

A further object is to provide a portable ventilating fan of light but strong construction which is adapted for use in a standing position or which may also be used satisfactorily in suspended position to provide a flow of air other than horizontal.

Other objects and advantages of the invention will be apparent from the following description, the accompanying drawing and the appended claims.

In the drawing—

Fig. 1 is a view in perspective of the front of a ventilating fan constructed in accordance with the present invention;

Fig. 2 is a view in perspective of the back of the fan shown in Fig. 1;

Fig. 3 is a view in side elevation of the fan shown in Fig. 1;

Fig. 4 is a view in horizontal section taken substantially on the line 4—4 of Fig. 3; and

Figs. 5 and 6 are diagrammatic views in per-

2

spective illustrating the use of the fan when suspended in different angular positions.

Referring to the drawing, which illustrates a preferred embodiment of the present invention, 5 the main frame for the fan is shown as a sheet metal panel 10 of rectangular shape having a large circular opening 11 through the center thereof. The metal surrounding this opening 11 is curved forwardly to form a flange 12 to provide a control ring for the fan, and panel 10 is also bent rearwardly along its edges to provide a rearwardly extending peripheral flange 13. A relatively narrow supplemental panel 15 or back strip has its ends curved forwardly at 16 and secured, as by welding, to the inner surface of flange 13 at opposite sides of main panel 10, thus positioning the main part of this supplemental panel in spaced parallel relation with the main panel and overlying the center of the opening 11. Also, the supplemental panel 15 is formed with an outwardly projecting rib 17 for increasing its rigidity.

An electric motor 20 is mounted on the supplemental panel 15, and extends with its drive shaft 21 substantially centrally through the opening 11 in the main panel. As best seen in Fig. 4, the mounting for this motor includes a plate 22 of relatively stiff sheet metal to which the motor is removably secured as by means of the nuts and bolts 23. This mounting plate extends substantially across the straight portion of supplemental panel 15 and has its ends 24 flanged as shown in Fig. 4 for attachment to the supplemental panel as by means of nuts and bolts 25. This construction provides for supporting the weight of the motor at spaced points on panel 15 so located that its curved portions 16 have a bracing action against twisting of the panel under the angular force imparted by the weight of the motor, and the sides 26 of plate 22 may also be bent over as shown to provide additional stiffening effect. Also, the flanged ends 24 of plate 22 provide for offsetting the plate from panel 15, as shown in Fig. 4, to accommodate the outer ends 40 of the mounting nuts and bolts 25 for the motor.

Referring particularly to Fig. 4, it will be seen that the motor 20 and its shaft 21 project through opening 11 and beyond the plane of the main panel 10, and in order to provide for compactness and to position the fan blades properly in the plane of the main panel to draw air through opening 11, a hub 30 of special design is used. As shown, this hub is secured to shaft 21 and includes at its rearward end a radially projecting flange 31, and this flange is extended to form three tabs

or fins 32 which are bent rearwardly and overlap the forward end of the motor. Fan blades 33 are in turn secured to these tabs 32, for example by bending the ends of the tabs outwardly and bolting or riveting the fan blades thereto. This construction thus provides for reducing the required depth of the fan as a whole from front to back to not substantially more than the axial length of the motor and its shaft while at the same time positioning the fan blades directly within the central opening 11 of the main panel 10 and substantially in the plane of this panel and control ring 12 for proper and efficient operation.

Protective screens are provided at both the back and front of the fan. Referring particularly to Figs. 2 to 4, the screen 40 at the back of the fan is shown as formed in two parts from a relatively close-mesh screening such as sheet metal grillwork. These two grills have their edges secured, as by welding, to the inner surfaces of flange 13 and supplemental panel 15, and they thus aid in bracing the supplemental and main panels relative to each other to provide further support for the weight of motor 20. The corners of screen 40 are curved, as shown particularly in Fig. 2, both for purposes of strength and to provide a rounded and pleasing appearance, and means are also provided for protecting these corners in transportation or use. Referring to Figs. 2 and 3, protective ribs 42 each have one end secured as by welding to the corners of flange 13 on the main panel 10, and these ribs are curved to overlie the corners of screen 40, with their outer ends free as shown in Fig. 2. These ribs thus serve to brace the corners of screen 40 and also to shield them in transportation and use.

The screen 44 at the front of the fan is shown as a relatively open-mesh wire screen having a rectangular outer rim 45 which is removably mounted at the front of main panel 10 by means such as the screw clamps 46. The remainder of screen 44 is curved forwardly and inwardly from its rim 45 to overlie the center of the fan and to shield the blades from coming into contact with any person or object in use, and as shown in Fig. 4, the middle portion of this screen is spaced from the supplemental panel 15 and back screen 40 by only slightly more than the axial length of motor 20 and its shaft 21, thus further contributing to the compactness of the fan. Also, the use of removable clamps 46 for mounting screen 44 facilitates its ready removal for replacement or servicing of the motor 20 or any of its associated or component parts.

Means are provided for supporting the fan for operation in an upright position, and these supporting means also serve to provide additional bracing for the main framework. Referring particularly to Figs. 2 and 3, the supporting means are shown as a pair of brackets or legs each including a horizontal portion 50 and a portion 51 extending upwardly from the rearward end of the horizontal portion 50. This upwardly extending portion of each leg is secured to the supplemental panel 15, as by means of one of the bolts 25 which connect the supplemental panel and the mounting plate 22 for the motor, and the horizontal leg portions 50 are similarly secured to the main panel 10, as by bolting to its peripheral flange 13, thus providing additional braces between the main and supplemental panels to support the weight and vibration of the motor and fan blades. As shown in Fig. 3, the horizon-

tal leg portions 50 extend from a position forward of the plane of main panel 10 to a position spaced rearwardly beyond the plane of supplemental panel 15, to provide an elongated supporting base 5 adapted to rest upon a suitable horizontal surface, and the opposite ends of leg portions 50 may also be equipped with suitable feet such as rubber grommets 52 as shown in Fig. 3. This construction provides for supporting the fan in well balanced upright position for operation, with the rearward feet 52 spaced sufficiently behind the plane of blades 33 to support the angular thrust on the fan in use and prevent its overturning.

A control switch is mounted on the fan in a convenient but relatively inconspicuous position. A switch box 55 is shown as mounted at the back of main panel 10 and adjacent one corner, where it will be substantially concealed by flange 13 and the rear screen 40, and the wires 56 from this switch to motor 20 are readily concealed by flange 13 and supplemental panel 15. The operating shaft for the switch is extended through the main panel 10 to a switch lever 57 conveniently located at the front of the main panel 10, and an electric cord 58 for transmitting current to the switch may be brought out through the mesh of screen 40 for attachment in a suitable wall socket or like outlet fixture.

It will accordingly be seen that the present invention provides a fan of simple and highly compact but strong and rigid construction which is adapted for use for many ventilating purposes. In these fans, the component parts of the frame are so formed and interconnected as to brace each other effectively against the stresses and vibrations incident to use and thus provide for the incorporation of fan blades and a motor of large capacity in a frame of convenient dimensions capable of portable use for many ventilation purposes. For example, fans constructed as described and shown in the drawing have been successfully produced and operated with blades of 9-inch radius in a frame only approximately 22 inches square by 7.75 inches from front to back including leg portions 50, and with a total weight of only about 25 pounds, and such a fan is capable of delivering an air flow as high as 1800 cubic feet per minute.

It will accordingly be seen that such fans can be placed on a window sill, or on a table or other supporting surface near a window, and will operate to provide forced ventilation either inwardly or outwardly of the window with no permanent mounting or other additional supporting parts and occupying very little space. Also, the compact construction of these fans further facilitates their portable use in that they occupy equally little space in storage or transportation, and at the same time they are of pleasing appearance in use. In addition, although they are rigidly constructed, the provision of a removable front screen permits easy access to the motor for servicing or even complete removal without effecting or loosening the other parts or otherwise weakening the frame for subsequent use.

The fans of the invention may also be used in suspended position, instead of being mounted on a supporting surface, and this is often desirable particularly to provide for directing the air stream at an angle to the horizontal. For such uses, the fan may readily be suspended by means such as chains attached to the front or back screens, and the construction of the fan as described and shown in Figs. 1 to 4 provides for such location of the center of gravity, that when the fan is suspended,

it will automatically tilt forward or backward, depending upon whether the suspending means are attached to the back or front screen, respectively. Such suspended mountings are shown in Figs. 5 and 6.

Referring to Fig. 5, a fan constructed as described in connection with Figs 1 to 4 is indicated generally at 60 as suspended in front of a window 61 and facing inwardly. The suspending means for the fan are shown as a pair of chains 62 each having one end attached to the adjacent side of the window frame and the opposite end attached to the back screen of the fan, for example by means of hooks 63 which are readily attached to the screen. Fig. 6 shows a similar mounting of the fan in which the chains 62 are attached to the front screen of the fan.

As shown in Fig. 5, when the suspending chains are attached to the back screen, the fan hangs in a forwardly tilted position, thus providing for directing the air flow into the room at a downwardly inclined angle. In the position shown in Fig. 6, the fan tilts backward and thus directs the air flow upwardly into the room. If the fan is turned to face the window, the air flow will be similarly angularly directed towards and out through the window.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A portable ventilating fan of the character described comprising a main panel having a central opening, a relatively narrow supplemental panel overlying said opening, means securing said supplemental panel to said main panel in spaced and parallel relation, a motor having a shaft, fan blades on said shaft of said motor, means mounting said motor on said supplemental panel with said fan blades positioned substantially centrally of said opening in said main panel, and means connected with both of said panels and constructed both to form supporting legs for said fan and to brace said panels relative to each other.

2. A portable ventilating fan of the character described comprising a main panel having a central opening, a relatively narrow supplemental panel spaced rearwardly from said main panel and arranged horizontally to overlie said opening, means securing said supplemental and main panels together, a motor having a drive shaft, means securing said motor to said supplemental panel and with said motor and shaft extending through said opening in said main panel, a fan having fan blades and a hub mounted on said shaft, said hub being spaced forwardly of said blades providing for positioning said blades substantially in the plane of said main panel, and screen means secured to both sides of said main panel to guard said fan blades, said screen means at the back of said main panel being also secured to said supplemental panel to brace said panels relative to each other.

3. A portable ventilating fan of the character described comprising a main panel of generally rectangular shape having a rearwardly extending peripheral flange, said panel having a central opening therethrough of substantial size, a relatively narrow supplemental panel having its ends secured to opposite sides of said main panel and with the remainder thereof spaced rear-

wardly from the plane of said main panel and extending horizontally across said opening, a motor, means mounting said motor on said supplemental panel substantially centrally of said opening in said main panel, fan blades operatively carried by said motor, and a pair of supporting legs for said fan each including a horizontal portion adapted to rest upon a supporting surface and an upwardly extending portion, said horizontal portion being secured to said main panel and said upwardly extending portion being secured to said supplemental panel to support said fan in an upright position and to brace said panels relative to each other.

4. A portable ventilating fan of the character described comprising a main panel of generally rectangular shape having a rearwardly extending peripheral flange, said main panel having a central opening therethrough of substantial size, a relatively narrow supplemental panel having its ends curved forwardly and secured to said flange at opposite sides of said main panel to space the remainder thereof rearwardly from the plane of said main panel and overlying said opening, a motor, means mounting said motor on said supplemental panel substantially centrally of said opening in said main panel, said mounting means being connected with said supplemental panel at spaced points adjacent said curved panel ends with said curved ends bracing the intermediate portion of said panel against the weight of said motor, fan blades operatively carried by said motor, protective screens mounted at the front and back of said main panel, and means secured to said main panel for supporting said fan in operative position.

5. A portable ventilating fan of the character described comprising a main panel of generally rectangular shape having a rearwardly extending peripheral flange, said main panel having a central opening therethrough of substantial size, a relatively narrow supplemental panel having its ends secured to opposite sides of said main panel and with the remainder thereof spaced rearwardly from the plane of said main panel and overlying said opening, a motor, means mounting said motor on said supplemental panel substantially centrally of said opening in said main panel, fan blades operatively carried by said motor, a protective screen mounted at the front of said main panel, a protective screen fixedly secured to said flange on said main panel and to said supplemental panel to protect the back of said fan and to brace said panels relative to each other, said front screen being of relatively open mesh, said back screen being of relatively close mesh and having curved corner portions, protective ribs for said screen corners secured at one end to said flange on said main panel and being curved over said screen corners with their opposite ends free, and means secured to said main panel for supporting said fan in operative position.

6. A portable ventilating fan of the character described comprising a main panel having a central opening, a relatively narrow supplemental panel overlying said opening, means securing said supplemental panel to said main panel in rearwardly spaced and parallel relation, a motor having a shaft, fan blades on said shaft of said motor, means mounting said motor on said supplemental panel with said fan blades positioned substantially centrally of said opening in said main panel, and supporting legs for said fan each including a horizontal portion adapted to rest

upon a supporting surface and secured to said main panel, said horizontal portion extending forwardly beyond the plane of said main panel and rearwardly beyond the plane of said supporting panel, each said leg also including a portion extending upwardly from the rearward end of said horizontal portion and secured to said supplemental panel to provide a brace between said panels and cooperating with said horizontal portion to support said fan for operation in an upright position.

7. A ventilating fan of the character described comprising a main panel having a central opening, a relatively narrow supplemental panel arranged in rearwardly spaced and parallel relation with said main panel, said supplemental panel being arranged horizontally of said opening, and having its end portions curved forwardly and secured to opposite sides of said main panel, a mounting plate removably secured to said supplemental panel, a fan motor secured to said mounting plate, said plate being of sufficient length to provide for securing opposite ends thereof to said supplemental panel at spaced points adjacent said curved ends of said panel and with said curved panel ends bracing the intermediate portion of said panel against the weight of said motor, fan blades operatively carried by said motor, a screen secured to said main and supplemental panels to protect the back of said fan and to brace said panels relatively to each other, a screen positioned at the front of said main panel, means removably securing said front screen to said main panel and providing for removal thereof for servicing of said motor, and supporting legs for said fan including horizontal portions extending from front to back thereof to support said fan at a plurality of spaced points, said horizontal leg portions being secured to said main panel, said legs including braces secured to said supplemental panel and to said horizontal leg portions to add additional rigidity to said fan construction.

8. A ventilating fan of the character described comprising a main panel having a central opening, a supplemental panel secured to said main panel and spaced rearwardly therefrom, front and back screens secured to said main panel, a motor having a drive shaft, the axial length of said motor and shaft being not substantially less than the distance between said supplemental panel and said front screen, a hub mounted on said shaft and provided with a radial flange, said flange having tab portions extending rear-

wardly therefrom substantially parallel to said shaft and radially beyond said motor, and fan blades secured to said tabs and positioned substantially in the plane of said main panel.

9. A ventilating fan of the character described comprising a rectangular main panel having a central opening and including a rearwardly extending peripheral flange, a relatively narrow supplemental panel spaced rearwardly from said main panel and having its ends curved forward and secured to said flange at opposite sides of said main panel, a screen having its edges secured to said flange and said supplemental panel to overlie the rear of said fan, protective ribs for the corners of said screen each secured at one end to the corners of said flange and curved to overlie the corners of said screen, a fan motor including a shaft, means for mounting said motor on said supplemental panel and extending through said opening in said main panel, a hub on said shaft including fins extending first radially and then rearwardly relative to the axis of said hub, fan blades secured to said fins and positioned thereby substantially in the plane of said main panel, a screen removably mounted on the front of said main panel, and means secured to said main and supplemental panels and adapted to rest on a horizontal surface to support said fan in an upright position.

10. A portable ventilating fan of the character described comprising a main panel having a central opening, a relatively narrow supplemental panel overlying said opening, means securing said supplemental panel to said main panel in spaced and parallel relation, front and back screens positioned at the front and back of said main panel and secured thereto, means for suspending said fan from a support, said screens being constructed for ready attachment to said supporting means, a motor having a shaft, fan blades on said shaft of said motor, and means mounting said motor on said supplemental panel with said fan blades positioned substantially centrally of said opening and with the center of gravity of said fan so located that said fan will tilt rearwardly when suspended with said suspending means attached to said front screen and will tilt forwardly when suspended with said suspending means attached to said back screen.
